UNITED STATES PATENT OFFICE

WILLIAM E. ANDERSON, OF TILLAMOOK, OREGON

SWING FOR CHILDREN

Application filed August 28, 1930. Serial No. 478,505.

This invention relates to a swing designed primarily for children's use, but it is to be understood that a swing, in accordance with this invention may be employed for any purpose for which it is found applicable, and the invention has for its object to provide, in a manner as hereinafter set forth for swinging simultaneously in horizontally revoluble and downwardly movable directions thereby affording considerable amusement and thrills to the occupants of the swing.

A further object of the invention is to provide in a swing, in a manner as hereinafter set forth, a revoluble element for carrying the occupants of the swing and which operates simultaneously in horizontally and downwardly movable directions and further including means for shifting said element from its lowermost position to the position for the descent thereof, when the occasion requires without removing the occupants of the swing from said element.

Further objects of the invention are to provide, in a manner as hereinafter set forth, a swing which is comparatively simple in its construction and arrangement, strong, durable, compact, thoroughly efficient in its use, conveniently operated when occasion requires, readily assembled and comparatively inexpensive to set up.

With the foregoing and other objects in view, the invention consists of the novel construction, combination and arrangements of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a front elevation of a swing in accordance with this invention, illustrating the swinging element in position for descent.

Figure 2 is a fragmentary view in vertical section of the swinging element with a seat swivelly connected thereto.

Figure 3 is a front elevation of the swinging element carrying a seat.

Figure 4 is a side elevation illustrating one of the seats.

Figure 5 is a fragmentary view in vertical section of the holder element and illustrating the revolving gear therefor.

Figure 6 is a detail in sectional plan illustrating the revolving gear for the holder element secured to the latter.

Figure 7 is a fragmentary view in front elevation of the swinging element and illustrating the means for coupling it to the interiorly threaded flanged bearing sleeve therefor.

Figure 8 is a fragmentary view in sectional plan of a bearing for the holder element.

Figure 9 is a fragmentary view in section.

Figure 10 is a sectional detail illustrating the latch for retaining the holder element in vertical position.

The swing includes a vertical supporting frame comprising a pair of side bars 1, 2 a top bar 3, a bottom bar 4 and a pair of inclined brace bars 5, 6 which have their upper ends secured to the upper ends of the side bars 1, 2 and the ends of the top bar 3. The brace bars 5, 6 incline outwardly from their upper towards their lower ends with respect to the side bars 1, 2. Each side bar is provided with a transversely disposed socket 7 which opens at the inner side edge of the bar. Extending into each socket is a bearing member 8 formed with an annular flange 9 which abuts against the inner edge of the side bar and is fixedly secured with the latter by the hold fast devices 10. The bearings 8 are positioned at the transverse center of the side bars 1, 2.

The swing includes a revoluble holder element referred to generally at 11. The element 11 is of skeleton form and of rectangular contour. The sides of element 11 are of greater length than the ends thereof. Each end of element 11 consists of a pair of tubular members 12, 13 connected together by a coupling 14 formed with legs 15, 16 and 17. The legs 15, 16 connect the tubular members 12, 13 together. One side of element 11 is formed of a pair of tubular members 18, 19

connected together by the coupling 20 formed with legs 21, 22 and 23. The legs 21 and 22 couple the members 18, 19 together. The other side of element 11 is formed from a single length of tubing indicated at 24. The members 18 and 19 are connected to the members 12 by the elbow couplings 25. The members 13 are connected with the tubing 24 by the elbow couplings 26. Bracing pieces 27 are arranged within and at the corners of the element 11. Hold fast devices, indicated at 28 may also be used to provide for securing members 12 and 13 to their couplings and members 18 and 19 together to their couplings. The legs 17 of the couplings 14 are arranged in alignment and extend towards each other.

Disposed lengthwise of the element 11 is a threaded rod 29 which has one end thereof extending into the leg 17 of one coupling 14 and has its other end extending into the leg 17 of the other coupling 14. Hold fast devices, indicated at 30 are employed for securing the rod 29 to coupling 14.

Each coupling 14 is notched or apertured as at 31 for the reception of a latch 32 for maintaining element 11 in a vertical position. The latch is of the spring controlled type and is carried by the bottom bar 4 of the supporting frame. The bar 4 seats upon a concrete block 33 and the latter is formed with a recess 34 having a beveled wall to provide a clearance for the latch 32 when the latter is depressed. It is to be understood that any suitable form of a latch for securing or maintaining the element 11 in a vertical position may be employed.

The swing includes swinging element which operates simultaneously in horizontally revolute and downwardly movable directions and which coacts with the rod 29. The swinging element referred to generally at 35, has threaded engagement with rod 29 and moves downwardly by gravity, but as it moves downwardly it revolves horizontally. The swinging element comprises a carrier 36 formed with an axial opening 37, and a pair of lengthwise extending openings 38, a pair of longitudinally disposed openings 39, each arranged at one end of the carrier. Connected to and extending through the openings 37 is an interiorly threaded flanged sleeve bearing 40. The sleeve 40 is flanged at each end and the flanges are indicated at 41, 42 and overlap the top and bottom surfaces of carrier 36. The flange 41 is formed with an opening or notch 43 and into which extends a spring controlled latch 44. The latter is mounted in the carrier 38 and when engaged in the flange 41, latches the carrier to the sleeve 41, in a manner to prevent rotative movement of the carrier relative to the sleeve on the downward movement of the sleeve. The threads of the sleeve are indicated at 45 and which mesh with the threads on the rod 29. The beveled

wall of slot 43 provides for the release of the latch.

Swivelly supported from each end of the carrier 37 is a seat 46, open at its top and front and provided with a safety chain 47. Positioned in each opening 39, as well as projecting from an end of the carrier 36, is a headed bolt 48. The head of the bolt 48 is indicated at 49 and is arranged at one end of an opening 38. The opening 39 is of a diameter materially less than the width of the opening 38. By this arrangement a shoulder 50 is provided against which the head 49 abuts. The shank of the bolt 48 projects from the end of the carrier and has threaded engagement with a head piece 51, provided with a U-shaped strap 52, which extends around the seat 46 and is fixedly secured therewith by the hold fast devices 53. A set screw 54 is carried by the head piece 51, bears against the shank of the bolt 48 and prevents turning of the head piece relatively to the carrier but bolt 48 is revolvable in the carrier 36.

Mounted on the rod 29 at each end portion thereof and bearing against the coupling members 14, are buffering springs or shock absorbing elements 55, 56.

Positioned against the outer side of the tubing 24, is a revolvable gear 57 for the holder element 11. Clamped to the tubing 24 are a pair of spokes 58 of the gear 57. The means for clamping the spokes 58 to the tubing 24 are indicated at 59 and interposed between the tubing 24 and spokes 58 are spacer members 60. The gear 57 is of the sprocket type, and it is so clamped to the holder element 11 that on the revolving of the gear, the holder element 11 will be carried therewith. The hub of the gear 57 is indicated at 61 and fixedly secured therewith is an outwardly directed stub shaft 62 which is revolvably mounted in the bearing 8 carried by the side bar 2 of the supporting frame. Fixedly secured to the coupling 20 and projecting outward therefrom is a stub shaft 63 which is revolvably mounted in the bearing 8 carried by the side bar 1 of the supporting frame.

Journaled in the side bar 2 of the supporting frame and projecting outwardly and inwardly with respect thereto, is a shaft 64 carrying on its outer end a hand wheel 65 and on its inner end a sprocket pinion 66. Travelling over the pinion 66 and gear 57 is an endless chain sprocket 67 to provide for revolving the holder element 11 when the wheel 65 is revolved.

The stub shafts 62 and 63 suspend the holder element 11 within the supporting frame. Upon the operation of wheel 65, the holder element 11 will be revolved in the supporting frame. The holder element 11 is releasedly retained to prevent the revolving thereof by the latching device 32. The latch 32 is of a spring controlled type whereby when the wheel 65 is revolved, a coupling

member 14 will clear the latch and permit of the holder element being revolved, until the other coupling element 14 is engaged by the latch 32.

5 The threads on the rod 29 are of spiral form and which in connection with the threads of the sleeve provides that when the carrier element 35 is in the position shown in Figure 1 for the element 35 to revolve, as the latter descends by gravity until it reaches the lower portion of bar 29, where it is checked in its downward course by a spring 56, but the element 35 continues to rotate until its momentum is exhausted. When the 10 carrier element abuts the spring 56 and its movement is discontinued, the holder element can then be revolved or turned carrying the element 35 therewith to position it at the upper portion of the supporting frame. The 15 holder is then latched and the foregoing operation is repeated, that is the revolving and descending of the element 35. As the seats 46 are swivelly connected to the carrier element, the occupants thereof will remain in an 20 upright position during the revolving of the holder element 11. When the holder element is revolved to position the carrier element 35 in a position of descent the coupling 14 which 25 opposes the bottom rod 4 of the supporting frame is engaged by the latch 32, whereby 30 the holder element 11 is retained in an upright position.

What I claim is:—

1. In a child's swing, a threaded element, 35 a gravity movable, revoluble carrier having a central opening, a longitudinal opening at each end terminal portion thereof and a shoulder at the inner end of each longitudinal opening, an interiorly threaded flanged sleeve 40 extending through said central opening and threadedly engaging with said element, a seat at each end of the carrier, a U-shaped strap secured to each seat and provided at one end with a head, and means extending 45 through said longitudinal openings, abutting said shoulders and fixed to said heads for swivelly suspending the seats.

2. In a child's swing, a revoluble threaded element, a gravity shiftable downwardly 50 movable revoluble carrier having an axial opening, said element being revolved in a direction at right angles to the revolving movement of said carrier, a bearing sleeve having flanged ends and interior threads, 55 said sleeve threadedly engaging with said element and having its flanges abutting the top and bottom of the carrier, said carrier and sleeve having coacting means for latching them together, an open top seat arranged at 60 each end of the carrier, and spaced means journaled in the carrier longitudinally of the latter, having their inner ends abutting the carrier within the latter and their outer ends extended from the carrier and fixedly secured 65 to the inner sides of the seats for swivelly

suspending said seats from the ends of the carrier.

3. In a child's swing, a horizontally disposed vertically movable, revoluble carrier formed at each end thereof with a length- 70 wise opening having its wall shouldered in proximity to the inner end of the latter, a pair of rotatable headed members extending through said opening, projected from the carrier and having their heads abutting said shoulders, a pair of seats, each having a part of its inner side inset, a strap secured to each seat and having a head at one end arranged in the inset of a side, and each of said members being secured to a strap head for swivel- 75 ly suspending the seats from the carrier. 80

In testimony whereof, I affix my signature hereto.

WILLIAM E. ANDERSON.
